UNITED STATES PATENT OFFICE.

WILLIAM W. TUCK, OF RICHMOND HILL, AND AUGUST WASSMANN, OF ASTORIA, NEW YORK, ASSIGNORS TO ABBOT AUGUSTUS LOW, OF HORSESHOE, NEW YORK.

PAPER-LIFTING MECHANISM.

SPECIFICATION forming part of Letters Patent No. 715,905, dated December 16, 1902.

Application filed February 21, 1902. Serial No. 95,023. (No model.)

To all whom it may concern:

Be it known that we, WILLIAM W. TUCK, residing at Richmond Hill, and AUGUST WASSMANN, residing at Halletts Point, Astoria, 5 Queens county, and State of New York, citizens of the United States, have invented certain new and useful Improvements in Paper-Lifting Mechanism, of which the following is a specification sufficient to enable others 10 skilled in the art to which the invention appertains to make and use the same.

Our improvements relate to what are known as "suction-fingers" in paper-manipulating mechanism, and are designed to render the 15 same more certain and positive in operation. As ordinarily constructed and used the suction-fingers are each formed with a single concavity on the under side. As a result, if there is any decided unevenness or irregularity of surface in the paper to be lifted and transferred or if the paper becomes bent or crumpled the suction exerted through the finger is ineffectual, since air leaks in between the paper and the edges of the suction-finger 20 and the requisite partial vacuum cannot be attained therein. We obviate this difficulty by forming the suction-finger with a plurality of openings on its under side, opening into a common vacuum-chamber, and by providing each opening with a valve which acts 25 automatically, if there is a leak of air into such opening, to close the passage into the main vacuum-chamber, and thereby allow the edges of the remaining openings to maintain 30 their hold on the paper.

In the accompanying drawings, Figure 1 is a longitudinal vertical section of our improved form of suction-finger; Fig. 2, a transverse section upon plane of line 2 2, Fig. 1; 40 Fig. 3, a view of the under side of the suction-finger.

The suction-finger F, in general form and arrangement, is essentially the same as those heretofore in use, being connected, by flexible tubing attached to its shank f, with suitable vacuum apparatus and being mounted and operating in the usual and well-known manner. The opening f' in the shank f communicates with the longitudinal vacuum-

chamber f², which, instead of having a single extended opening in the under side of the finger-piece, is formed with a series of air-ducts a a, which open into valve-chambers, formed in turn with openings d d, the lips of which bear upon the paper. The air-valves 55 c c may be of any desired form. In the construction shown in the drawings they consist of balls c c, slightly larger in diameter than the ducts a a, and suction-openings d d. Thus when the paper to the surface of which 60 the suction-finger is applied is smooth and even the suction exerted through the openings d d draws the adjoining paper against the lip-openings d d and holds it there as long as the partial vacuum is maintained within the 65 chamber f². In case, however, of a rough or uneven surface under or adjoining one of the openings d air will rush into that particular valve-chamber and force its valve c against the air-duct a, thereby preserving the partial 70 vacuum in the chamber f² and maintaining the hold of the other openings d d upon the paper.

Any desired or suitable number of openings and valves may be provided for the vacuum-finger. The greater the number employed the greater will be the certainty and delicacy of operation of the finger, which is practically rendered positive in action by our invention.

What we claim as our invention, and desire to secure by Letters Patent, is—

1. A device for lifting and transferring sheets of paper formed with a vacuum-chamber having a plurality of openings in which 85 are situated loosely-mounted automatic air-valves each confined wholly within its opening, for the purpose set forth.

2. A suction-finger for lifting and transferring sheets of paper formed with a vacuum-chamber having a plurality of air ducts and chambers in each of which is situated a loosely-mounted automatic valve confined wholly within its chamber, for the purpose set forth.

3. In a suction-finger F, the combination of the common vacuum-chamber f², the series of air-ducts a a, the ball-valves c c, and

the suction-ports d, d , arranged and operating substantially in the manner and for the purpose described.

4. A suction-finger F having tubular shank, 5 continuous vacuum-chamber, a series of air-ducts leading therefrom, independent chambers into which said ducts lead, the bottom of said finger having openings, the lips of which are adapted to bear upon the paper, and

ball-valves loosely mounted in such chambers of greater diameter than said ducts and suction-openings, and adapted to serve substantially as shown and described.

WILLIAM W. TUCK.
AUGUST WASSMANN.
